UNITED STATES PATENT OFFICE

120,667

DESIGN FOR AN IDLER BRACKET FOR CONVEYERS OR THE LIKE

John James Fairbairn, Roosevelt, N. Y., assignor
to Robins Conveying Belt Company, Passaic,
N. J., a corporation of New Jersey

Application February 20, 1940, Serial No. 90,375

Term of patent 14 years

To all whom it may concern:

Be it known that I, John James Fairbairn, a citizen of the United States, residing at Roosevelt, in the county of Nassau and State of New York, have invented a new, original, and ornamental Design for an Idler Bracket for Conveyers or the like, of which the following is a specification, reference being had to the accompanying drawing, forming part thereof.

Figure 1 is a side view of an idler bracket for conveyers or the like showing my new design; Fig. 2 is an inner face view of the bracket, and Figs. 3 and 4 are transverse sections on the lines 3—3 and 4—4 of Figs. 1 and 2, respectively.

I claim—

The ornamental design for an idler bracket for conveyers or the like, substantially as shown.

JOHN JAMES FAIRBAIRN.
